ATTORNEY

UNITED STATES PATENT OFFICE.

GEORGE W. CUMMINGS, OF TROY, NEW YORK.

KNITTED FABRIC.

1,027,696.

Specification of Letters Patent. Patented May 28, 1912.

Application filed October 2, 1911. Serial No. 652,345.

To all whom it may concern:

Be it known that I, GEORGE W. CUMMINGS, a citizen of the United States, residing at Troy, county of Rensselaer, and State of New York, have invented certain new and useful Improvements in Knitted Fabrics, of which the following is a specification.

The invention relates to such improvements and consists of the novel construction 10 and combination of parts hereinafter described and subsequently claimed.

Reference may be had to the accompanying drawings, and the reference characters marked thereon, which form a part of this 15 specification.

Similar characters refer to similar parts in the several figures therein.

Figure 1 of the drawings represents diagrammatically and in exaggerated form a 20 piece of my improved fabric showing the loops of filling-thread laid out flat upon the respective sides of the fabric. Fig. 2 is a similar exaggerated diagrammatic view showing a horizontal section taken through 25 certain of the stitch-loops and certain of the floating threads which connect the stitch-loops together, and showing the manner in which the filling-thread is woven back and forth through the meshes between the neighboring vertical rows of stitches in the knitted web.

The principal object of the invention is to produce a knitted fabric having on both 30 sides substantially the surface appearance of, and adapted for the uses of, Turkish toweling or similar uncut-pile woven fabric.

Other objects, however, will appear in connection with the following description.

In carrying out my invention in its preferred form, I weave back and forth 40 through the meshes of a knitted web of fabric, filling-thread forming projecting loops prominently exposed upon, and substantially covering, both sides of the knitted web, and forming uncut pile-surfaces 45 for the fabric. Filling-thread may be thus interwoven with the knitted web during, and as part of, the knitting operation performed either by hand or machine.

50 In the drawings I have shown my invention applied to a preferred form of knitted web, which may be made upon an ordinary spring-needle cylinder by the use of a one-and-one cut presser, the filling-thread being laid into or interwoven with the knitted

web by means of suitable burs coöoperating with said cylinder.

Referring to the drawings wherein the invention is shown in preferred form, the 60 stitches or stitch-loops, 1, appear in vertical rows, the stitches in one row being connected, respectively, with stitches in another row by floating threads, 2 and 2^a, forming vertical rows of meshes alternating with the vertical rows of stitch-loops.

65 In the preferred form of my invention, I employ a plurality of filling-threads, 3 and 4, each appearing in prominently projecting loops upon both sides of the fabric. The filling-thread, 3, thus appears in loops, 3^a, 70 upon one side of the fabric and in loops, 3^b, upon the opposite side of the fabric, while the filling-thread, 4, appears in loops, 4^a, upon one side of the fabric and in loops, 4^b, upon the opposite side of the fabric. The 75 filling-threads are woven back and forth through the meshes between the vertical rows of stitch-loops, the loops of each filling-thread on one side of the fabric embracing the respective stitch-loops, 1, of the 80 knitted web, while the loops of said filling-thread on the opposite side of the fabric embrace, respectively, floating threads, 2 or 2^a. Two filling-threads are employed in the preferred form of my invention; and the loops 85 of filling-thread on one side of the fabric embrace the respective stitch-loops of the knitted web, while the loops of one of said filling-threads on the opposite side of the fabric embrace the alternate floating threads 90 between neighboring vertical rows of stitch-loops, and the loops of the other filling-thread on the opposite side of the fabric embrace, respectively, the remaining floating threads. Thus each stitch-loop, 1, is 95 embraced by a loop, 3^b, and a loop, 4^b, of the respective filling-threads, 3 and 4, and the alternate floating threads, 2^a, are embraced by the respective loops, 3^a, of the filling-thread, 3, and the remaining floating 100 threads, 2, are embraced by the respective loops, 4^a, of the filling-thread 4.

105 In a fabric made in the manner described, both sides of the fabric will be substantially covered by the projecting loops of filling-thread, giving to the fabric a heavy body and absorbent qualities adapting it for many uses, and particularly for toweling.

110 For certain purposes of the invention, the knitted web may be formed in any known

manner, and any desired number of filling-threads may be employed and so interwoven through the meshes of the knitted web as to attain the objects above set forth.

- 5 For certain purposes of my invention the loops of filling-thread, whether formed by a single thread or a plurality of threads, are so elongated that they are adapted to overlap one another upon either side of the web, 10 and are adapted to overlap other rows of stitches of the knitted web than the rows from which said elongated loops respectively project.

In the preferred form of my invention, 15 the elongated loops of filling-thread overlap one another and substantially cover both surfaces of the knitted web.

What I claim as new and desire to secure by Letters Patent is—

- 20 1. A fabric comprising a knitted web and filling-thread woven back and forth through the meshes between vertical rows of stitches in said web, and prominently exposed in the form of projecting loops upon both sides of 25 the web, said loops upon one side of the web embracing the respective stitches in said vertical rows, and said loops upon the opposite side of said web embracing, respectively, floating threads which connect together

stitches in one with stitches in another of 30 said vertical rows.

2. A fabric comprising a knitted web and filling-thread interwoven therewith and exposed in prominent loops upon the surface of the fabric, said web having each of its 35 floating threads which connect together stitches in different vertical rows, embraced by a filling-thread.

3. A fabric comprising a knitted web and a plurality of filling-threads, woven back 40 and forth through the meshes between neighboring vertical rows of stitches in said web, said filling-threads being prominently exposed in the form of projecting loops upon the surface of the fabric, loops of one 45 of said filling-threads embracing respectively certain, only, of the floating threads which connect together stitches in different vertical rows, and loops of another of said filling threads embracing certain other, only, 50 of said floating threads.

In testimony whereof, I have hereunto set my hand this 30th day of September, 1911.

GEORGE W. CUMMINGS.
